CLAIM

The ornamental design for a game pack, as shown and described.

DESCRIPTION

FIG. 1 is a perspective view of a game pack showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The new and original container set forth in this specification is separable into two halves defined by the dark line seen in FIGS. 1, 4, 5, 6 and 7 on the circumference of the container so that items, such as confectionery pieces, may be placed in and removed from the container.
